UNITED STATES PATENT OFFICE.

GRANVILLE C. ROGERS, OF LA CROSSE, WISCONSIN.

TUMBLER-WASHER.

1,087,260.

Specification of Letters Patent. Patented Feb. 17, 1914.

Application filed June 11, 1913. Serial No. 773,075.

To all whom it may concern:

Be it known that I, GRANVILLE C. ROGERS, a citizen of the United States, residing at La Crosse, in the county of La Crosse and State of Wisconsin, have invented certain new and useful Improvements in Tumbler-Washers; and I do hereby declare the following to be a full, clear, and exact description of the invention, such as will enable others skilled in the art to which it appertains to make and use the same.

This invention comprehends improvements in tumbler washers and relates more particularly to that class of devices which may be operated so as to cause water to be sprayed against the interior and exterior of a number of tumblers or glasses simultaneously.

One of the objects of the invention is the provision of a tumbler washer which shall be of extremely simple construction, compact, and capable of washing one or more tumblers at a single operation.

Another and more specific object of the invention is the provision of a tumbler washer including a plurality of perforated trays for the support of the tumblers, and a plurality of spraying hoods positioned over the trays and adapted to be forced against tumblers positioned on the trays.

As a still further object, the invention contemplates the provision of novel water controlling means including spring valves which are held normally closed but open under pressure and permit water to be sprayed against the tumblers.

With these and other objects in view, as will become more apparent as the description proceeds, the invention consists in certain novel features of construction, combination, and arrangement of parts, as will be hereinafter described and claimed.

For a complete understanding of my invention, reference is to be had to the following description and accompanying drawings, in which,

Figure 1 is a top plan view of my improved tumbler washer, Fig. 2 is a vertical sectional view taken on the plane of line 2—2 of Fig. 1, parts of the device being shown in elevation, Fig. 3 is a vertical sectional view taken on the plane of line 3—3 of Fig. 1, with parts of the device shown in elevation, Fig. 4 is a detail bottom plan view of a spraying hood, Fig. 5 is a detail top plan view of a perforated tumbler sup-

porting tray, Fig. 6 is a detail sectional view through a spraying hood and nozzle, the valve being shown in elevation, and, Fig. 7 is a vertical sectional view through one of the perforated trays, spraying nozzle, and coöperating parts, the valve and valve stem being shown in elevation.

In the preferred embodiment of my invention, the washer is of such construction as to be capable of cleaning three glasses or tumblers simultaneously, but it is to be understood that the device may be constructed so as to clean in one operation, as many tumblers as desired.

My washer is adapted to be positioned over a rinsing tank and has a base formed by the rods 10 and main water line or conduit, generally designated 11. The rods 10 which are four in number are connected in pairs by means of the four-way couplings 12 and 13, the rods of each pair being connected to opposite sides of their respective coupling and extending at right angles to the conduit 11. This conduit is formed by a plurality of short pipes 14 and the three-way couplings 15 and 16. The outermost pipes are connected to the couplings 12 and 13, respectively, and to the couplings 15, whereas the inner pipes are connected to the coupling 16 and to the couplings 15. A feed pipe 17 is connected to the coupling 18 which in turn is connected to the coupling 12 by means of the pipe 19. Water may flow through the feed pipe 17, the main conduit 11, to the coupling 20, which is connected to the coupling 13 by means of the pipe 21. A water motor 22 may be driven by water flowing through the pipe 23 from the coupling 20. A valve 24 controls the flow of water to the motor and said motor is for the purpose of driving a brush 25 which is useful in cleaning the interior of the glasses and tumblers. A branch pipe 26 extends rearwardly from the coupling 16 and connects to a coupling 27 which performs the same function as the couplings 15.

A nozzle 28 which, as is clearly shown in Fig. 7, consists of a cylindrical body having one end closed by a head 29 formed with the openings 29' and its other end reduced in diameter and externally threaded, is screwed within each of the couplings 15 and 27. A sleeve 30 telescopes over the outer end of each of the nozzles and is connected to one of the segmental tumbler supporting trays 31. One of these trays is shown in detail

in Fig. 5 and it will be seen that they are perforated and formed with a central opening in which the sleeve 30 is secured. A spider 32 is positioned within the upper end 5 of each sleeve and is rigidly connected to a depending valve stem 33 which carries a valve 34 that seats against the lower end of the nozzle so as to prevent water flowing therein. An expansive spiral spring 35 surrounds the valve stem and by bearing 10 against the head 29 and the spider 32 holds the valve normally seated. In order to insure a proper seating of the valve when pressure is removed from the tray 31, I 15 provide an expansive spiral spring 37 which acts in conjunction with the spring 35, and which surrounds the nozzle and sleeve and bears against a plate 38 and the under side of the tray, as clearly shown in Fig. 7. The 20 peculiar shape of the trays is such as to require a minimum amount of space and this will be apparent upon reference to Fig. 1.

Guide rods 39 having the heads 40 are threaded into the couplings 18 and 20 and 25 are disposed in a vertical position for the purpose of guiding the reciprocatory cross bar 41. This bar is held normally in its uppermost position by means of expansive spiral springs 42 which are housed within 30 the telescoping casings 43. The upper sections of the telescoping casings are secured to the cross bar 41 and the lower sections are rigid with the couplings 18 and 20.

The means for directing water upon the 35 exterior of the inverted tumblers is supported by the cross bar 41. This means includes a main coupling member 44 which is connected to a vertical handle 45 and the pipes 46 and 47. The pipes 46 extend parallel with the bar 41 and the pipe 47 extends 40 rearwardly from the coupling. Nozzles 48, similar in construction to the nozzles 28, are extended through the bar 41 and threaded into the couplings 49, which are connected 45 to the extremities of the pipes 46. A nozzle 50 is threaded into the three-way coupling 51 carried by the pipe 47. A valve 52 seats upon the upper open end of each of the nozzles and carries a depending valve 53 which is connected to a concavo-convex plate 54 forming a part of the spraying hood, generally designated 55. This hood has a neck or sleeve portion 56 which telescopes upon the lower end of the nozzle, 55 as clearly shown in Fig. 6. An expansive spiral spring 57 insures a proper seating of the valve. Water is conveyed from the main conduit to the spraying hoods by means of a flexible tubing 58 which is connected to the couplings 27 and 51.

Having described the construction of my tumbler washer, it now remains to explain the operation thereof.

The tumblers to be washed are supported 65 in an inverted position upon the perforated

trays 31, one tumbler being disposed upon each of the trays. The spraying hoods are then forced downwardly by means of the handle 45 into contact with the bottoms of the tumblers. When sufficient downward pressure is exerted the trays are forced 70 downwardly against the tension of the springs 35 and 37, and unseat the valves 34, allowing water to flow from the main conduit through the nozzles 28 into the tumblers. As the lower valves are being opened, the springs 57 are compressed and the valves 52 raised from the ends of the nozzles 48 and water is discharged into the spraying 75 hoods and flows through the perforated plates 55 onto the exterior of the tumblers. If one glass or tumbler is to be cleaned, a downward movement of the spraying hoods will open only those valves which will permit water to flow against the tumbler and thus it will be seen that there is no waste of water. As soon as the downward pressure is removed from the handle 45, the bar 41 raises the spraying hoods from engagement with the tumblers and the 80 valves 34 and 52 automatically close.

From the foregoing description taken in connection with the accompanying drawings, it will be seen that I have provided a very simply constructed tumbler washer 85 which is of a compact form and which will operate to simultaneously spray the interior and exterior of a plurality of tumblers. The spraying hoods are positioned directly over the centers of the supporting trays so 90 that when the tumblers are properly positioned upon the trays, they will be engaged by the hoods when the latter are forced downwardly.

It is to be understood that while I have 10 shown and described the preferred embodiment of my invention, I do not wish to be limited to this exact construction, combination, and arrangement of parts, but may make such changes as will fall within the 11 spirit and scope of the invention as defined by the appended claims.

Having thus described my invention, what I claim is:—

1. In a tumbler washer, a tumbler support, means whereby water may be forced upwardly through this support when the latter is forced downwardly, a spraying hood positioned over the tumbler support, and means whereby, when said hood is forced downwardly into engagement with a tumbler, water may be allowed to flow into the hood.

2. A tumbler washer including a main conduit, vertical spraying nozzles in communication with said conduit, spring pressed valves normally closing the passages through said nozzles, a tumbler supporting member positioned above each of the nozzles and adapted to open the controlling valve there- 1

for when forced downwardly, a spraying hood positioned over each of the tumbler supporting members, means for conveying water from the main conduit to said spraying hoods, and valves adapted to open when the spraying hoods are forced downwardly into engagement with tumblers positioned upon the tumbler supporting members.

3. A tumbler washer including a main water conduit, a plurality of vertical spraying nozzles in communication with said conduit, perforated trays positioned over said nozzles, valves adapted to close the passages through the nozzles when the trays are in their raised positions, spring means for normally holding said trays in their raised positions, a depending spraying nozzle supported over each of the trays, means for conveying water from the main conduit to said depending spraying nozzles, and spring pressed valves adapted to normally close the passages through the depending spraying nozzles, a downward movement of the depending spraying nozzles into engagement with inverted tumblers positioned upon the trays, causing both sets of valves to be opened.

4. In a tumbler washer, a base comprising a main water conduit and supporting rods extending at right angles to said conduit from adjacent the ends thereof, a plurality of spring pressed perforated trays each of which is adapted to support a tumbler in an inverted position, means for causing water to spray upwardly through said trays when they are forced downwardly, a reciprocatory member positioned above the trays, and means carried by the reciprocatory member for engagement with inverted tumblers, whereby the trays are lowered and water caused to spray upwardly.

5. In a tumbler washer, a base comprising a main water conduit and a plurality of supporting rods extending at right angles from adjacent the ends thereof, a plurality of individually movable tumbler supporting trays, means whereby water may be directed upwardly through said trays when they are forced downwardly, a pair of guide standards, a reciprocatory bar movably connected to said standards, a plurality of spraying hoods supported by said bar, one hood being positioned directly over each of the supporting trays, means for directing water into said spraying hoods, and valves for opening and closing the passages through said means, a downward movement of the reciprocatory bar serving to bring the hoods into engagement with tumblers supported upon the trays and open the valves.

6. In a tumbler washer, a tumbler supporting tray, means whereby a downward movement of the tray will permit water to be sprayed upwardly therethrough, a spraying nozzle positioned over the tray, said nozzle having a cylindrical body open at each end, a spraying hood having a neck slidable upon the spraying nozzle, a valve stem secured to the hood and extending through the nozzle, and a valve carried on the upper end of the valve stem for engagement with the upper end of the nozzle, and movement of the hood into forceful engagement with the tumbler positioned upon the tray, causing the valve to open, whereby water may flow through the nozzle and hood.

In testimony whereof I affix my signature in presence of two witnesses.

GRANVILLE C. ROGERS.
